(57) **CLAIM**

The ornamental design for a paint container and lid construction, as shown and described.

DESCRIPTION

FIG. 1 is a perspective view of a first embodiment of a paint container and lid construction showing a closed container; FIG. 2 is a perspective view of a first embodiment showing the lid in an in-use position; FIG. 3 is a top plan view of a first embodiment thereof; FIG. 4 is a bottom plan view of a first embodiment thereof; FIG. 5 is a front elevational view of a first embodiment thereof; FIG. 6 is a rear elevational view of a first embodiment thereof; FIG. 7 is a right side elevational view of a first embodiment thereof; and, FIG. 8 is a left side elevational view of a first embodiment thereof.

The broken lines shown in the drawing views are included for the purpose of showing environmental structure that forms no part of the claimed design.
